UNITED STATES PATENT OFFICE

167,092

BOOT FOR DOGS

Harry E. Monroe, Los Angeles, Calif.

Application November 19, 1951, Serial No. 17,466

Term of patent 14 years

(Cl. D7—4)

To all whom it may concern:

Be it known that I, Harry E. Monroe, a citizen of the United States, residing at Los Angeles, in the county of Los Angeles and State of California, have invented a new, original, and ornamental Design for a Boot for Dogs, of which the following is a specification, reference being had to the accompanying drawing, forming a part thereof.

Figure 1 is a perspective view of a boot for dogs, showing my new design.

Fig. 2 is a side elevational view thereof.

Fig. 3 is a rear view thereof.

Fig. 4 is a bottom plan view thereof.

I claim:

The ornamental design for a boot for dogs, as shown.

HARRY E. MONROE.
